UNITED STATES PATENT OFFICE.

JOHN C. JONES, OF BROOKLINE, MASSACHUSETTS.

LIFTING DEVICE.

1,410,924.

Specification of Letters Patent. Patented Mar. 28, 1922.

Application filed January 26, 1920. Serial No. 354,053.

To all whom it may concern:

Be it known that I, JOHN C. JONES, of Brookline, in the county of Norfolk and State of Massachusetts, have invented a new and useful Lifting Device, of which the following is a specification.

The principal object of my invention is to provide a lifting device, which is especially adapted for use with automobiles, and which has power and quickness of action but which is cheap to manufacture.

A feature of my invention is an actuator to engage the end of the lifting member.

Another feature is an oscillatory actuator having a specially formed actuating periphery.

Another feature is an actuator having a continuous movement in one direction to accomplish the entire lifting.

Another feature is the automatic lowering of the lifting member.

Another feature is the holding member acting independently of the actuator.

Another feature is that all the principal elements, which are few in number, may be of cast metal.

Other features will be pointed out below. In the drawing

Figure 1 is a front elevation of my lifting device;

Figure 2 is a side elevation thereof; and

Figure 3 is a fragmentary section of the holding member.

The cast metal supporting frame has an enlarged flat base portion A with integral reinforcing parts a , a' and a^2 connected integrally with wall A' and similar integral reinforcing parts such as a^3 and a^4 integrally connected with wall A². These walls A' and

A² have an integral reenforcing band a^6 connecting them at the front and rear and also an integral connecting portion a^7 . The walls A' and A² are perforated to receive the shaft B which is integral with hub B',

the latter having two passages b and b' extending therethrough and being at a right angle to each other and adapted to receive the removable turning member B². It will be understood that any desired number of openings in the hub B' may be provided to receive the turning member, which may be of any suitable length.

The actuating member D is preferably of cast metal and has a perforation for the shaft B and has a fixed connection with said

shaft by means of a split rivet d' although any other suitable device could be used. The flat periphery of the actuating member is shaped as shown and the purpose of said shaping will be described below.

The lifting member E is preferably a single casting comprising teeth e and a curved seat e' which is located centrally of the device and is well adapted to engage an axle of an automobile. The whole space however between the prongs e² and e³ is available as a seat. Integral with member E, I provide another seat E' which may be conveniently used to engage a member which is lower than the member to be engaged by seat e'.

Roller E² is pivotally mounted at the end of member E forming an operative part thereof.

Pivoted to the frame as by rivet f is holding dog F which is preferably of cast metal and which has a prong f' to engage the desired tooth e and which has an integral extension f² of substantial weight so as normally to hold the end of prong f' in the path of teeth e. When said prong is in its normal position its under side bears on shoulder f³ so that substantially all the resistance is furnished by said shoulder and substantially none by the rivet.

I preferably attach a spring G to the outside of wall A' to bear against hub B' in order to give a slight brake effect.

When the member E is in its lowest position the roll E² will rest in the depression d of the periphery of member D and hold said member D against undesired swinging. When the device is to be operated the member B² is inserted in the desired opening and the member D is turned in the direction of the arrow, the portion d² increasing rapidly in its distance from the axis so as to give great lifting power at the start of the lift. The increase from the point d³ to the end d⁴ is more gradual and it will be understood that this portion may be extended beyond d⁴ by making member D larger if it is desired to give more travel to the lifting member. As the latter is raised the prong f' will ride along the teeth e and when the lifting member has been raised to the desired point the portion f² will swing prong f' inwardly so that it engages the flat portion of the adjacent tooth and firmly holds the lifting member in its raised position, jamming the member E against the adjacent

portions of the frame. When the lifting member is to be lowered the member D will be turned slightly in the direction of the arrow whereupon the prong f' may be 5 swung out of the path of the teeth e so as to permit lowering of member E. This lowering is automatic, that is to say, the weight of the automobile or other lifted thing will compel rotation of member D in 10 the direction opposite to that indicated by the arrow and member E will move slowly down to its lowest position, this automatic closing being preferably accomplished by the disclosed shape of the periphery of member D. While the friction of the parts would undoubtedly be sufficient to ensure 15 slow lowering of member E yet if desired the spring G may be used. Of course the lowering may be controlled by member B² or even by a slight grip of the hand on hub B'.

It will be observed that member B² may be applied in different openings of the hub as may be convenient in view of the particular rotative position which said hub may 20 occupy at any given time.

It will also be observed that the member B² may be operated entirely by the foot because the pressure to be applied may be downward on said member both for raising 30 member E in its general upward movement and for the slight raising to permit unlocking of the prong f'.

An important advantage of my device is that I provide an actuator having continuous 35 rotary motion in one direction to move the lifting member through its entire travel and to give great power and at the same time a long lifting distance.

Another important advantage is that my 40 device will not easily get out of order and even if it should it may be entirely and easily disassembled by removing the two rivets.

Another advantage is that the hub may be 45 turned by hand until the lifting member engages the member to be lifted and then the turning member may be inserted so that the turning member may do all the actual lifting without being removed from the hub.

50 What I claim is:

1. A device of the character described comprising a lifting member; a pivoted actuating member having a periphery to engage the end of said lifting member and thereby raise the lifting member, that portion of the periphery which engages the lifting member during the first portion of the raising increasing rapidly in its distance from said pivot and the remainder of said 55 periphery increasing more gradually in its distance from said pivot.

2. A device of the character described comprising a supporting frame; a lifting member mounted to move longitudinally 60 within said frame; a holding member

pivoted to said frame; a shaft pivoted to said frame and being provided with a fixed hub; an oscillating actuator directly engaging said lifting member and fixed to said shaft and mounted to swing within said frame and preventing undesired axial movement of said shaft, the axis of said actuator being in line with said lifting member, and a brake spring for the shaft arranged between the frame and hub. 70

3. A device of the character described comprising a lifting member movable longitudinally; a shaft having a fixed axis, which is in line with said lifting member; an oscillatory member fixed to said shaft and having a periphery to directly engage the end of said lifting member, said periphery continuously increasing in its distance from the axis of the oscillatory member throughout the lifting movement, the oscillatory member having another peripheral part provided with a plurality of peripheral engaging portions, and a removable handle adapted for engagement with any one of said portions to operate the oscillatory 80 member. 85

4. A device of the character described comprising a lifting member movable longitudinally; a shaft having a fixed axis, which is in line with said lifting member; an oscillatory member fixed to said shaft and having a periphery to directly engage the end of said lifting member, said periphery continuously increasing in its distance from the axis of the oscillatory member throughout the lifting movement, the oscillatory member having another peripheral part provided with a plurality of peripheral engaging portions; a removable handle adapted for engagement with any one of said portions to operate the oscillatory member, and means independent of the oscillatory member to hold the lifting member in the desired 90 position. 95

5. A lifting jack including a frame, a longitudinally movable lifting member slidably mounted in the frame, and an oscillating cam mounted in the frame and having its axis in alignment with the plane of movement of the lifting member, said cam having an operative surface engaging said lifting member, and the radius of said surface from said axis rapidly increasing in length from its leading portion to a point intermediate its ends, and gradually increasing in length from this point to the trailing portion of said surface. 100 115

6. A jack as defined in claim 5 provided with means for holding the lifting member in adjusted positions independently of said cam. 125

7. A jack as defined by claim 5 in which the cam is provided with an abutment surface, which when the lifting member is in lowered position, projects outwardly from 130

the frame and is adapted to be engaged by the operator's foot to permit initial operation of the cam without manual operation.

8. A jack as defined by claim 5 in which 5 the cam has its central portion removed to reduce weight and to permit the insertion of the operator's foot for initially actuating the cam by pressing downwardly with the foot.

9. A jack of the kind described including 10 a movable lifting member, a frame member supporting the same, an actuator for the lifting member, one of said members being provided with a series of teeth, a pivotally mounted pawl engageable with said teeth, 15 and an abutment surface on the frame member arranged to be engaged by the pawl for relieving the pawl pivot of the weight supported by the lifting member.

10. A jack including a frame, a reciprocating lifting member mounted in the frame and provided with a series of teeth, an actuator for the lifting member, a pawl pivotally mounted in the frame and engageable with said teeth, and an abutment sur-

face provided on the frame and arranged to 25 be engaged by the pawl for relieving the pawl pivot of the weight supported by the lifting member.

11. A device of the character described comprising a lifting member movable longitudinally in direct engagement with the article to be lifted; a shaft having a fixed axis which is in line with said lifting member; an oscillatory member fixed to said shaft and having a periphery to directly 30 engage the end of said lifting member, said periphery continuously increasing in its distance from the axis of the oscillatory member throughout the lifting movement, and extending angularly through more than 35 180° with reference to said axis, the oscillatory member having another peripheral part provided with a plurality of peripheral engaging portions; and a removable handle adapted for engagement with any one of 40 45 said portions to operate the oscillatory member.

JOHN C. JONES.
